UNITED STATES PATENT OFFICE.

FRANCIS J. HAGE, SR., OF GOLDSBORO, NORTH CAROLINA.

AWNING.

SPECIFICATION forming part of Letters Patent No. 693,129, dated February 11, 1902.

Application filed December 11, 1900. Serial No. 39,508. (No model.)

To all whom it may concern:

Be it known that I, FRANCIS J. HAGE, Sr., a citizen of the United States, residing at Goldsboro, in the county of Wayne and State 5 of North Carolina, have invented a new and useful Awning, of which the following is a specification.

This invention relates to improvements in awnings; and the object is to provide a portable awning having simple attaching means whereby it may be readily put up and taken down and whereby when not needed it may be removed from the window, so that it will not be exposed to the elements.

With the above object in view the invention consists in the novel features of construction hereinafter fully described, particularly pointed out in the claims, and clearly illustrated by the accompanying drawings, in 20 which—

Figure 1 is a perspective view of an awning constructed in accordance with my invention; Fig. 2, a face view of the window-frame with the awning removed, showing the fastening devices carried by the frame; Fig. 3, a vertical sectional view of the same; Fig. 4, a detail view illustrating the manner of connecting the supporting-rope with the upper 25 end of the awning; and Fig. 5, a perspective view of the frame for the lower portion of the awning, showing the spring attaching members carried thereby.

Referring now more particularly to the drawings, A A designate screw-eyes fixed in 35 the window-frame, on the exterior thereof, and B a screw-eye attached to said frame intermediate of the eyes A A.

C designates a rope which is passed through the central screw-eye and extended in opposite directions and passed through the eyes A A. The central looped portion D of this rope constitutes an operating portion to raise and lower the upper end of the awning, as will be hereinafter set forth. The ends of 40 the rope are secured to attaching members, each member consisting of an eye E, in which the rope is secured, and a transversely-extending arm F, projecting on each side of the eye. These attaching members are inserted 45 through screw-eyes G, fixed in a bar or slot

H, attached to the upper end of the awning I, as illustrated by Fig. 4 of the drawings. J designates a frame comprising three sides of a rectangle, the front bar of said frame being provided with a series of perforations K. The frame is positioned with its perforated bar on the inner side of a strip of cloth I', secured to the inner side of the awning, and the perforated bar L is positioned on the outer side of said strip, lacing M being used to secure 60 said frame to the strip, said lacing passing through the perforations of the bar L and the front bar of the frame and through the strip which is held therebetween. The side bars of said frame J have secured to them two spring-metal plates N, having their free ends curved in opposite directions to form finger portions O. The spring members are formed adjacent to their curved ends with half-sockets P, designed to coact with each other to form a 65 socket when the finger portions are pressed toward each other, said socket receiving the shank Q, projecting from a plate R, secured to the side of the window-frame and provided with a head S. Cleats T are secured to the 70 window-frame to receive the central operating portion D of the rope when the awning has been drawn upwardly to its proper place. In operation to attach the awning the attaching devices carried by the ends of the rope C are 75 inserted through the eyes at the upper end of the awning and the awning drawn upwardly and held by attaching portion D of the rope to one of the cleats T. The frame at the lower end of the awning is then attached to the window-frame by placing the yielding attaching members of said frame in engagement with the shanks Q of the plates R.

The operation of removing the awning will be readily understood from the above description, it being apparent that it may be as conveniently and quickly removed from the window as applied thereto.

Instead of detaching the awning from the window when it is no longer necessary to serve 90 as a protection against the rays of the sun arms J may be swung upwardly upon the studs Q, which to a certain extent will raise the awning, or the upper end of the awning 95 may be lowered by the rope D and the arms 100

I swung downwardly. The construction, however, is such that the awning may be readily removed from the window when its use is no longer necessary—as, for instance, in the 5 evening.

Having thus fully described my invention, what I claim as new, and desire to secure by Letters Patent of the United States, is—

1. An awning comprising a covering, a frame attached to the lower end of the covering, yielding attaching members carried by the ends of said frame, coacting attaching members adapted to be secured to the window-frame, an elevating-rope adapted to be attached to the window-frame, and attaching means carried by said rope to engage the upper end of the covering, and the screw-eyes through which the said rope passes, substantially as described.
2. An awning comprising a covering, a frame secured to the lower end of the covering, spring-arms carried by the ends of the frame, projections adapted to be secured to the window-frame and to extend between said

spring-arms, an elevating-rope adapted to be 25 carried by the window-frame and attaching means carried by said rope and adapted to engage the upper end of the covering, and the screw-eyes through which the said rope passes, substantially as shown and described.

3. An awning comprising a covering, a frame carried by the lower end of said covering, spring-arms carried by the ends of said frame and provided with finger portions, plates adapted to be secured to the window-frame and formed with headed projections to extend between the spring-arms, an elevating-rope adapted to be carried by the window-frame and attaching means carried by said rope and adapted to engage the upper end of 35 40 said covering, and the screw-eyes through which the said rope passes, substantially as described.
